UNITED STATES PATENT OFFICE.

HARRY E. COLE, OF AKRON, OHIO, ASSIGNOR TO THE COLE FOLDING BOX COMPANY, OF AKRON, OHIO, A CORPORATION OF OHIO.

CONTAINER.

Application filed April 25, 1925. Serial No. 25,763.

This invention relates to folding boxes usually manufactured of cardboard, although the invention may be applied to containers of paper or other material.

5 The object of the present invention is to provide an improved form of folding box structure which can be manufactured from a single blank and easily and quickly folded into box form, the box when folded being a 10 complete container and provided with interlocking features so that it cannot open or spread. In the particular form of the invention illustrated and described, a box is shown suitable for the packaging of pneumatic tubes, but the principles of the invention may be applied to boxes or containers of other shapes and of all sizes and proportions and the invention is not limited to the exact 15 details or arrangement of parts shown 20 herein.

Other objects and advantages are provided by the improved structure in which are secured simplicity, ease of folding, and complete interlocking of the various 25 elements of the box in folded form.

In the drawings is shown the preferred form of the invention, in which

Figure 1 is a plan view of the box blank with the various lines of folding indicated 30 thereon;

Figure 2 is a perspective view of the box at the completion of the first folding operation;

Figure 3 is a longitudinal section on the 35 line 3—3 of Figure 4 showing the third folding operation partially completed;

Figure 4 is a view looking into the box of Figure 3;

Figure 5 is an enlarged perspective of the 40 open end of the box;

Figure 6 shows the box in folded form with one form of interlock;

Figure 7 is a section of Figure 6 on the plane 7—7 of the latter figure;

Figure 8 is a view of the same box folded in slightly different form; and

Figure 9 is a section on the line 9—9 of Figure 8.

In describing the invention the form of 50 blank shown in Figure 1 will first be detailed, the terms, front, ends, side, back, etc., referring to the position of the various parts of folds of the blank as they are situated in the completely folded box of Figures 6 55 and 8.

The blank shown herein is the form substantially of a rectangle cut to shape and scored so as to facilitate folding, the scoring dividing the blank into the various parts as will be described. 1 is the bottom of the 60 box, 2 the top, 3 the closed end and 4 the open end. These four elements of the finished box are arranged in a line through the center of the blank, the open end carrying a small locking tab 5 which is also in line with 65 the four parts just described. At the sides of the bottom 1 are the parallel side walls 6 and at the sides of the top 2 are similar parallel side walls 7 which, for the sake of distinguishing, may be termed the bottom 70 and top side walls respectively.

At the sides of the closed end 3 are located the gussets 8 which lie between the side walls 6 and 7 and are preferably scored by crossing diagonal scorings 9 to facilitate the 75 folding of the box. This scoring may be of any preferred form so that the gussets will fold properly. In the form illustrated, there is shown a species of scoring such as covered in my prior Patent No. 1,230,675 of June 19, 80 1917. The gussets are rectangular in shape, but do not extend quite to the edges of the side walls between which they are located, the outer edges of the gussets thereby not interfering with the folding of the box. 85

At the ends of the top side walls are formed wings 10, the outside edges of which are inset slightly, as at 11, so as not to interfere with the tucking-in of the wings. The outside corners of the wings are scored upon 90 diagonal lines to form small triangular tips 12. The inside corner of each wing is cut away on a diagonal line 13, a small projection 14 being left at the inside corner to effect interlocking of the box. 95

At the ends of the bottom side walls and at either side of the open end are provided flaps 15 which are substantially rectangular, but the edges of which are set in from the outer edges of the side walls and open end 100 so as not to interfere with the folding. Each flap is scored as at 16 in the same manner as the gussets so that it can fold together when the box is formed in shape and thereby form pockets adapted to receive the wings and tips 105 when the box is folded or set up. In the top, slightly set back from its outer edge, is arranged a transverse slit 25, which provides a bridge piece 26 and the edge may be cut out to form a notch 17. The tab 5 is formed 110

with oppositely arranged pairs of cuts 18 and 19, on its edges the former cuts being short and close to the open end. The latter cuts are somewhat longer and are spaced 5 from the open end a distance equal to the width of the bridge piece 26.

Having described the blank as it is cut out, the folding operations and the construction of the finished box will be understood.

10 The first operation is to bring the side walls at right angles to the blank to the position shown in Figure 2 along the lines 20. The bottom side walls are now held by the thumbs and second fingers while pressure exerted by the first fingers upon the gussets causes them to fold along the scored lines 9 and brings the top over the bottom of the box, the top side walls enclosing the bottom side walls as shown in Figures 3 and 15 20. 4. When the top is brought down the wings 10 lie outside of the flaps 15, the wings coinciding with the space 22, bounded by the scores 16, and the tips 12 lying outside of the space 23. As the open end 4 is 25 brought up the wings 10 are located within the pockets formed by the folds of the flap and the tips 12 are secured within the pockets formed by the folds so that the wings are securely locked in place. The 30 projections 14 will interlock with the cuts 18 while the tab 5 passes beneath the top. The notch 17 provides a purchase for opening the box. If a further interlock for the open end is desired, the tab may be passed 35 through the slit 25, in which case the cuts 19 will interlock with the slit. The bridge 26 may be pressed inwardly to release the open end.

The box formed in the manner stated is 40 easy and inexpensive to manufacture and will securely hold when in folded condition. The invention is not necessarily limited to the utilization of every feature in a single box, as some of them may be utilized without all of the other features.

What is claimed is:

1. A folded box made from a one-piece blank comprising a sheet of material having defined therein a top, closed end, bottom and 50 open end in a line through the center of the sheet, top and bottom side walls laterally of the top and bottom, respectively, flaps located in the angles between the bottom side walls and the open end, each flap being subdivided by score lines into a plurality of triangular areas which are adapted to form 55 pockets when folded, wings projecting beyond the ends of the top side walls, and tips upon said wings and defined therefrom by 60 score lines, so that when the box is folded,

the wings are adapted to lie within pockets formed by the folds of the flaps and the tips are adapted to lie in overlying pockets, whereby an interlocking closure may be formed when the box is set up.

65

2. A folded box made from a one-piece blank comprising a sheet of material having defined therein a top, closed end, bottom and open end in a line through the center of the sheet, top and bottom side walls laterally of the top and bottom, respectively, flaps located in the angles between the bottom side walls and the open end, each flap being subdivided by score lines into a plurality of triangular areas which are adapted to form a 70 pocket when folded, and wings projecting beyond the ends of the top side walls, so that when the box is folded, the wings are adapted to lie within the pockets formed by the folds of the flaps, whereby an interlocking closure may be formed when the box is set up.

75

3. A folded box made from a one-piece blank comprising a sheet of material having defined therein a top, closed end, bottom and open end in a line through the center of the sheet, top and bottom side walls laterally of the top and bottom, respectively, gussets between the top and bottom side walls, said gussets being scored so as to fold together, flaps located in the angles between the bottom side walls and the open end, each flap being subdivided by score lines into a plurality of triangular areas which are adapted to form pockets when folded, wings projecting beyond the ends of the top side walls, tips upon said wings and defined therefrom by score lines, so that when the box is folded, the wings are adapted to lie within pockets formed by the folds of the flap and the tips are adapted to lie in overlying pockets, whereby an interlocking closure may be formed when the box is set up, and a tab extending beyond the open end adapted to 85 form an interlock between the open end and the top.

80

4. A folded box made from a one-piece blank comprising a sheet of material having defined therein a top, closed end, bottom and open end in a line through the center of the sheet, top and bottom side walls laterally of the top and bottom, respectively, wings projecting beyond the ends of the top side walls, a tab projecting beyond the open end, projections from the wings located at the corners thereof adjacent the top, and slits formed in the line between the tab and the open end with which the projections are adapted to interlock when the box is set up.
